UNITED STATES PATENT OFFICE.

ROBERT H. BOYD, OF PHILADELPHIA, PENNSYLVANIA.

VENTILATING SHOE-TREE AND DISPLAY-FORM.

No. 927,104.

Specification of Letters Patent.

Patented July 6, 1909.

Application filed February 29, 1908. Serial No. 418,456.

To all whom it may concern:

Be it known that I, ROBERT H. BOYD, a citizen of the United States, residing at Philadelphia, in the county of Philadelphia and State of Pennsylvania, have invented 5 certain new and useful Improvements in Ventilating Shoe-Trees and Display-Forms, of which the following is a specification.

My invention relates to improvements in a 10 ventilating shoe tree and display form.

The object of my invention is to construct a shoe tree which will distend the shoe without covering the entire inner surface of the leather forming the shoe, which would prevent 15 the leather from properly drying.

A further object of my invention is to provide a retiform covering for the frame work of the shoe tree.

A further object of my invention is to construct 20 a shoe tree which may be readily inserted and withdrawn from a shoe; which will be simple in operation and which can be manufactured at a very low cost.

Referring to the drawings: Figure 1 is a 25 perspective view of my improved shoe tree; Fig. 2 is a longitudinal section through the same, with the wire gauze covering removed; and, Fig. 3 is a cross section on line 3—3 Fig. 1.

In the drawings the toe portion 1 of the shoe tree is shown constructed by using a continuous wire 2 secured at one end at the point 3 and coiled spirally throughout the toe portion 1 of the shoe tree. The said wire 2 is continued 35 throughout the central portion 4 of the shoe tree, but instead of being coiled spirally the wire 2 is formed into loops 5, forming a space between the adjacent ends of the said loops for the admission of the fingers, 40 to operate the adjusting screw and levers. The wire 2 is continued from the central portion 4, of the shoe tree, to the heel portion 6, which is also formed by coiling the wire 2 spirally, the end of which is fastened at the 45 point 7 to the rib 8. The said rib 8 is fastened at the points 10 and 12 to the first coil of the wire 2 forming the heel 6 of the shoe tree.

The toe portion 1 of the shoe tree is provided 50 with a rib 14, secured at the points 15 and 16 to the wire 2. This rib 14, conforms to the shape of the toe of the shoe tree and is soldered to the several coils of the wire 2, forming the toe portion. A similar rib 18 is 55 secured to the wire 2, at the points 19 and 20, it extends horizontally throughout the toe

portion of the shoe tree and is soldered to the several coils of the wire 2 in a manner similar to the rib 14. These ribs 14 and 18 tend to support the coils of the wire 2 and assist the toe portion of the shoe tree to maintain its proper shape.

The shoe tree in Fig. 1 is shown covered with a retiform fabric 22 constructed of wire, cloth or other suitable material, which extends over the toe or heel portions of the shoe tree or over both as desired. The said fabric covering assists the shoe tree in maintaining its proper shape and adds to the general appearance of the same, but it is to be understood that it is not an essential feature of my invention as it may be dispensed with and the shoe tree still perform its proper functions.

When the shoe tree is being inserted or 75 withdrawn from the shoe it is desirable to contract the same, this I accomplish in the following manner: Cross-pieces 24 and 25 are secured in the toe and heel portions respectively. Said cross-pieces are formed of flat 80 plates, secured in any suitable manner, to the toe and heel portions, in the drawings, the said plates 24 and 25 are secured to the ribs 14 and 8 respectively, by bending the ends of said plates around the wires forming said 85 ribs.

Between the plates 24 and 25 are levers forming a knee joint, by the action of which the toe and heel portions may be forced apart or drawn together. The said levers comprise, the connecting-lever 26 pivoted to the cross-piece 25, secured in the heel portion and the adjusting-lever 27 pivoted to the 90 said connecting-lever 26, by the pin 28 and to the cross-piece 24, carried by the toe portion, by the pivot pin 29.

The adjusting-lever 27 is made in two sections 30 and 31, which are provided with screw-threads running in opposite directions. Upon the ends of said sections 30 and 31 is 100 placed a sleeve 32 provided with right and left hand screw-threaded portions corresponding to the ends of the sections 30 and 31 of the adjusting-lever 27. The sleeve 32 is provided with a thumb-screw 33, so that said 105 sleeve may be readily turned by the fingers and the adjusting-lever shortened or lengthened whereby the shoe tree may be adjusted to fit shoes of different sizes.

The adjusting-lever 27 and the connecting-lever 26 are bifurcated at the ends where they are pivoted to the cross pieces 24 and

25, so that said levers will be held from turning axially, but will be free to move in a vertical plane on the pivot-pins. The inner ends of said levers 26 and 27 are provided with beveled ends 34 and 35 which strike the shoulders 36 and 37, when the levers are expanded, and will hold said levers in a practically straight line, and rigidly lock the toe and heel portions when expanded. When 10 the levers are moved into the position shown in Fig. 2 the toe and heel portions will be drawn close together.

Having thus described my invention I claim and desire to secure by Letters Patent.

15 1. A shoe tree or display form comprising a toe portion formed of a number of coils arranged in a transverse direction to the length of said shoe tree or display form.

20 2. In a shoe tree or display form, the combination of a toe portion formed of rings arranged in a transverse direction to the length of said shoe tree or display form and a rib to support said rings.

25 3. In a shoe tree or display form, the combination of a toe portion formed of a number of coils, a heel portion formed of a number of coils, said coils arranged in a transverse direction to the length of said shoe tree or display form and means for connecting said toe and heel portions.

30 4. In a shoe tree or display form the combination of a toe portion, a heel portion and a central portion, said central portion formed of several loops, said loops arranged in a transverse direction to the length of said shoe tree or display form.

35 5. In a shoe tree or display form the combination of a toe portion and a heel portion, said heel portion formed of a number of coils, said coils arranged in a transverse direction to the length of said shoe tree or display form.

40 6. In an article of the character described the combination of a toe portion constructed of rings, a rib to support said rings, a heel portion and a central portion connecting said toe and heel portions.

45 7. In an article of the character described

the combination of a toe portion, a heel portion constructed of rings, a rib to support 50 said rings and a central portion connecting said toe and heel portions.

8. In an article of the character described, the combination of a toe portion formed of a continuous wire coiled spirally, said coils arranged in a transverse direction, a central portion formed by said wire, said wire forming said central portion being formed into loops extending in a transverse direction to the length of said central portion and said 60 loops so arranged as to form a longitudinal opening at the top of said central portion and said wire continued beyond said central portion and curved to form a heel portion.

9. A shoe tree or display form comprising 65 a toe portion formed of a number of coils arranged in a transverse direction to the length of said shoe tree or display form and said toe portion incased in a retiform fabric.

10. In an article of the character described 70 the combination of a toe portion constructed of several coils, a rib to support said coils, a retiform fabric to incase said coils, a heel portion and means to connect said toe and heel portions.

11. In an article of the character described the combination of a toe portion formed of a continuous wire coiled spirally, a central portion formed by said wire, said wire being bent into loops throughout said central portion to form an opening at the top of said central portion, said wire continued and curved to form the heel portion, a cross-piece secured to the wires forming said toe portion and a cross-piece secured to the wires of said heel 80 portion, levers pivotally connected to said cross-pieces, said levers adapted to contract or expand said central portion and means for varying the length of said levers.

In testimony whereof I affix my signature 85 in presence of two witnesses.

ROBERT H. BOYD.
